UNITED STATES PATENT OFFICE.

FREDERICK L. MCGAHAN, OF LOS ANGELES, CALIFORNIA; VIOLA K. WALKER, ADMINISTRATRIX OF SAID FREDERICK L. MCGAHAN, DECEASED, ASSIGNOR TO THE PURPOSED MIND DEVELOPMENT SECURITY ASSOCIATION OF THE WORLD, A TRUST COMPANY.

FILTER.

Original application filed January 3, 1918, Serial No. 210,146. Patent No. 1,292,399, dated January 19, 1919. Divided and this application filed January 17, 1919. Serial No. 271,719.

To all whom it may concern:

Be it known that I, FREDERICK L. MCGAHAN, a citizen of the United States, residing at the city of Los Angeles, in the county 5 of Los Angeles and State of California, have invented certain new and useful Improvements in Filters, of which the following is a specification.

This application is a division from the 10 application of the same inventor for patent for locomotive filed January 3, 1918, Serial 210,146 which became Patent 1292399 Jan. 19, 1919, and relates more particularly to the filter for the water obtained by con- 15 densation of the steam utilized in driving the turbine described in the said application.

In the accompanying drawings forming part of this specification, in which like numbers of reference denote like parts wherever 20 they occur,

Figure 1 is a top plan view;

Figure 2 is a vertical longitudinal sectional view;

Figure 3 is a side elevation of a locomotive showing the filter in situ; and

Figure 4 is a rear elevation for the same purpose.

The exhaust from the turbine 1 that forms the characteristic feature of the said patent, 30 is into the steam condenser and water-cooler 2 shown in Figures 3 and 4. The said exhaust passes through pipes (not shown) into the said condenser 2. The condenser 2 is formed of a plurality of square pipes 3, ar- 35 ranged as shown in Figures 3 and 4, which, by reason of their form and arrangement, and particularly because of the serpentine course that the steam is obliged to pursue therethrough (as indicated by the arrows in 40 Figure 3) cause condensation of the steam and its cooling because of the large area of pipe through which it passes before it reaches the exit. This exit is into pipe 4 that leads to the filter 5 (shown in detail in 45 Figure 2). The condensing effect of the said large area of pipe is augmented by the draft that flows among the pipes 3 when the locomotive is in motion, which draft is enhanced by the hood 6 that encloses the 50 said pipes 3, except at their ends.

The water product of the condensation of steam in the condenser 2 is purified in filter

5. As shown in Figure 2 and indicated in Figure 1, this filter or purifier 5 consists of three compartments constructed of any suitable material with walls 7 and partitions 8. Openings 9 and 10 permit the flow of water through the filter, entering through pipe 4 into chamber 11; thence passing through opening 9 into chamber 12; and thence passing through opening 10 into chamber 13. From chamber 13 the water passes out of the filter through pipe 14.

In compartment 11 is contained crushed copper glance. In compartment 12 charcoal is contained. Compartment 13 contains crushed lime-rock.

Thus the water entering through pipe 4 leading from condenser 2 flows in a serpentine course, as indicated by the arrows in 70 Figure 2, first, through the crushed copper glance of compartment 11, then through opening 9 into compartment 12, and by the action of gravity travels downward through the charcoal compartment 12; thence it 75 passes through opening 10 into compartment 13 where it rises through the crushed lime-rock and flowing outward through the pipe 14 to the water reservoir 15, from which it is pumped by pump 16 as distilled water to 80 the boiler (not shown).

It has been found that the use of copper glance, otherwise known as cuprous sulphide, operates to prevent the fine particles of oil and organic matter that might be 85 present in the water as it comes from the condenser or source of supply from passing through the charcoal and lime rock. When the water passes through the copper glance, the copper glance thereby becomes hydro- 90 lyzed and the hydrolyzed copper so formed serves to separate the oil and organic matter from the water and thus prevents these substances from passing to the compartments containing the charcoal and lime 95 rock. It will thus be seen that there is provided a filter that will take care of the very fine particles in suspension in the water and which would pass through the charcoal or the lime rock into the boiler 100 causing corrosion and incrustation.

This filtering of water does away with any sediment or residue such as is commonly found in boilers and does away with clean-

ing or blowing out of boiler tubes, which is a great advantage over types of boilers heretofore known.

It will be understood that both condenser 5 2 and water reservoir 15 may be located at any suitable place on the locomotive, and may be borne or supported thereby in any suitable manner.

Having thus described this invention, I 10 hereby reserve the benefit of all changes in form, arrangement, order, or use of parts, as it is evident that many minor changes may be made therein without departing from the spirit of this invention or the 15 scope of the following claims.

I claim—

1. A filter having three vertically disposed chambers, an inlet at one end of the first chamber and an outlet at its other end and 20 into the second and an exit from the second at the opposite end from its inlet, the said exit forming an inlet into the third chamber, an outlet from the last mentioned chamber at the end thereof opposite its inlet and 25 in alignment with the central longitudinal axis thereof, the filter material in the first

mentioned chamber being crushed copper glance, in the second chamber charcoal, and in the third chamber crushed limerock.

2. A filter divided into three vertically disposed chambers and having an inlet pipe at its beginning and an outlet pipe at the top and in alignment with the central longitudinal axis of the third chamber at its outlet, there being a communicating opening at or near the top of and between the first two chambers and another communicating opening at or near the bottom of and between the second and third chambers.

3. A filter having three chambers in communication with each other so that the liquid passed through the filter will traverse each of said chambers, filtering material in said chambers, the first chamber containing crushed copper glance; the second or intermediate chamber containing charcoal, and the third and last chamber containing crushed limerock.

In testimony whereof I hereunto affix my signature.

FREDERICK L. McGAHAN.
